UNITED STATES PATENT OFFICE.

LEWIS L. HEPBURN, OF NEW HAVEN, CONNECTICUT, ASSIGNOR TO THE MARLIN FIREARMS COMPANY, OF NEW HAVEN, CONNECTICUT, A CORPORATION OF CONNECTICUT.

SAFETY DEVICE FOR REPEATING FIREARMS.

SPECIFICATION forming part of Letters Patent No. 776,322, dated November 29, 1904.

Application filed April 1, 1904. Serial No. 201,028. (No model.)

To all whom it may concern:

Be it known that I, LEWIS L. HEPBURN, a citizen of the United States, residing at New Haven, in the county of New Haven, State of Connecticut, have invented certain new and useful Improvements in Safety Devices for Repeating Firearms, of which the following is a full, clear, and exact description.

My invention relates to improvements in repeating firearms.

My invention has for its object the improvement of the safety device made the subject-matter of my former patent, No. 662,427, dated November 27, 1900, in which patent I have described my safety device as applied to a repeating firearm constructed after the manner shown in my former patent, No. 528,905, dated November 6, 1894.

In the accompanying drawings, Figure 1 is a side elevation, partly in section, of the breech portion of a repeating firearm equipped with my improved safety device, the latter being shown in the locking position. Fig. 2 is a similar view, the safety device being shown in the unlocking position. Fig. 3 is a plan view of the cartridge-carrier and the safety locking device, said parts being detached from the balance of the mechanism of the gun. Fig. 4 is a side elevation of the cartridge-carrier detached. Fig. 5 is a side elevation of the safety locking device detached and enlarged relatively to Figs. 1 and 2. Fig. 6 is a front elevation of the parts shown in Fig. 5. Fig. 7 is a view of the opposite side of the parts shown in Fig. 5. Fig. 8 is a rear elevation of the parts shown in Fig. 6.

Since I have shown my improved safety locking device in connection with the repeating firearm made the subject-matter of my former patent, No. 528,905, I shall describe in general terms the parts which are in common to both cases.

1 is the receiver. 2 is a breech-block adapted to reciprocate in said receiver. 3 is a locking-bolt. 4 is a carrier. 7 is a hammer. 8 is a firing-pin. 14 is an inertia-piece. 15 is a spring arranged to normally move the inertia-piece into its locking position. (See Fig. 1.)

16 is a hook carried by the inertia-piece, said parts 14 and 16 having slight independent 50 swinging movement, for the purpose herein-after described. 16^a is a spring arranged to cause said hook to normally stand in the position shown in Figs. 1 and 2 relatively to the said inertia-piece. 17 is a shoulder on the 55 locking-bolt 3, with which the hook 16 engages when the parts are locked. 18 is a spring-pressed stud or detent having a beveled end and carried by the inertia-piece 14. 19 is a shoulder or abutment preferably having 60 one beveled face, said shoulder being formed on the carrier 4 and provided for the purpose herein-after described. 20 is a cast-off device by which the operator may manually release the safety locking device whenever desired. 65

The operation of the parts above described is substantially as follows: When the operator desires to use the firearm, he causes a loaded shell to be introduced into the barrel, whereupon the breech-block 2 is advanced and the 70 locking-bolt 3 is tilted to effectively prevent the said breech-block from being moved back so long as it stands in a tilted position. When the parts are thus arranged, the hammer 7 is at full-cock, it being automatically set. When 75 the hammer 7 is cocked, the firing-pin 8 stands over the rear end of the locking-bolt 3, and prevents it from being tilted, and hence the firing-pin constitutes the main locking device of the gun which I am describing. When the user pulls the trigger and the hammer springs forward and drives the firing-pin ahead against the cartridge, the latter should explode, but if it should hang fire there is no danger of a premature unlocking of the gun, 85 because although the firing-pin has moved into a position in which the locking-bolt is freed, so far as the main locking mechanism is concerned, it is, nevertheless, effectively held by the hook 16, which engages the shoulder 17. This safety locking device therefore prevents any premature unlocking of the gun. When the cartridge explodes, the inertia-piece 14 swings forward and if the shoulder 17 does not bind the hook 16 the latter will also move 90 ahead simultaneously with the inertia-piece 95

14. If, however, the shoulder-piece 17 should bind hook 16, the inertia-piece will start to move in advance of the hook 16 and will gain a momentum sufficient to knock off the hook 5 when the wall at the rear of the recess in which the hook is carried hits against said hook. (See dotted lines, Fig. 5.) The safety locking device will then assume the position shown in Fig. 2, in which position the locking-bolt 3 is entirely free so that the breech mechanism may be opened. Obviously some suitable means should be provided for temporarily holding the safety locking device in the position shown in Fig. 2, pending the extraction and ejection of the empty cartridge-shell. The means shown and described in this case correspond to the means shown and described in my former patent, No. 682,427. This means operates as follows: When the carrier 4 stands in the elevated position shown in Figs. 1 and 2, the spring-pressed detent 18 engages with the shoulder 19 on the carrier. As soon as the breech-block 2 is retracted the carrier 4 descends, removing the shoulder 19 25 from the detent 18, whereupon the safety locking device springs back to its normal position ready to engage the locking-bolt, when the breech mechanism is again closed and the locking-bolt tilted.
- 30 From the foregoing description it will be seen that ordinarily the safety locking device will act in a manner similar to that described in my former patent, No. 662,427; but in the event there should be anything tending to bind the hook 16 or hold it from a free swinging movement the inertia-piece is still free to swing ahead upon the recoil of the gun, so that it will acquire a momentum which will be sufficient to overcome any binding or frictional engagement of the hook and cast it off. In the construction referred to in my former patent, wherein the hook and the inertia-piece have no independent movement, it might happen that the hook might be frictionally engaged by the locking device to such an extent that the recoil would not be sufficient to dislodge the same, and hence although the cartridge might be discharged the gun would still be locked. In the use of my former device if this should occur the inertia-piece could be manually cast off; but in the present invention of course the possibility of this occurring
- is substantially, if not entirely, avoided. This is accomplished entirely by having this slight independent movement of the inertia-piece 55 relatively to its hook.
- What I claim is—
1. In a firearm in combination, a frame, a movable breech-block, a locking-bolt therefor, an inertia-piece carried by the frame, a hook 60 carried by the inertia-piece having limited independent movement relatively thereto and arranged to interlock with said locking-bolt and be disengaged therefrom by the recoil of the gun, a carrier and means on the carrier for retaining the inertia-piece after recoil.
2. In a firearm in combination, a frame, a movable breech-block, a locking-bolt therefor, an inertia-piece carried by the frame, a hook carried by the inertia-piece but having slight 70 independent movement relatively thereto said hook interlocking with said locking-bolt and being disengaged therefrom by the recoil of the gun, a carrier, means on the carrier for retaining the inertia-piece after recoil, and 75 means for returning said inertia-piece into engagement with the locking-bolt.
3. In a firearm in combination, a frame, a movable breech-block, a locking-bolt therefor, an inertia-piece pivotally supported on the 80 frame, a hook also pivotally supported on the frame and coöperating with the inertia-piece but having slight independent movement, a carrier and means on the carrier for temporarily retaining the inertia-piece after recoil. 85
4. In a firearm in combination, a frame, a movable breech-block, a locking-bolt therefor, an inertia-piece carried by the frame, a hook separate from said inertia-piece but carried thereby and having slight independent movement relatively thereto said hook interlocking with said locking-bolt and disengaged therefrom by the recoil of the gun, a carrier 90 and means for temporarily engaging the inertia-piece with the carrier after recoil said means comprising shoulders upon each of said parts one of said shoulders being yielding and spring-controlled.

Signed at New Haven, Connecticut, this 29th day of March, 1904.

LEWIS L. HEPBURN.
